APPARATUS FOR HEAT TREATING RAILS

Percival Hunter, Jr., Chicago, Ill., assignor to The
Oxweld Railroad Service Company, a corpora-
tion of Delaware

Application May 13, 1937, Serial No. 142,434

15 Claims. (Cl. 266—5)

This invention relates to apparatus for heat treating the tread surfaces of rails, especially at rail joints, and more particularly to portable apparatus which can be moved along a track for hardening tread surface areas with high temperature heating flames.

One of the principal objects of the invention is to provide an improved apparatus of the character specified which is easily constructed, of minimum weight and efficient in operation. Another object is to provide such an improved apparatus having heating units for each rail of a track, so as to avoid the necessity of shifting the entire apparatus in proceeding along a section of track which is being heat treated. Other and more specific objects are: to provide such an apparatus in which the heating units are mounted upon an operating structure or supporting frame, said operating structure being pivotally mounted upon a primary frame structure which is adapted to be moved along the track; to provide means for oscillating and adjusting the heating units simultaneously; to provide improved means for controlling the gases supplied to the heating unit; and to provide improved means for moving the apparatus along the track being treated.

The above and other objects and novel features of the invention will become apparent from the following description, having reference to the accompanying drawings, in which:

Figs. 1 and 2 are respectively front elevational and plan views of one form of apparatus embodying the principles of the present invention;

Fig. 3 is an end elevational view of a major portion of the apparatus shown in Fig. 1;

Fig. 4 is a vertical sectional view of the apparatus, taken along the line 4—4 of Fig. 1;

Fig. 5 is a fragmentary vertical sectional view taken along the line 5—5 of Fig. 3;

Fig. 6 is a diagrammatic view, corresponding approximately to the line 6—6 of Fig. 3, and showing particularly the location of the heating tips with respect to a rail joint;

Figs. 7 and 8 are respectively plan and front elevational views of a modified form of primary frame structure upon which the operating structure shown in Fig. 1 may be pivotally mounted; and

Fig. 9 is a plan view, mainly diagrammatic, of a modified arrangement of the gas controlling devices.

As shown in Figs. 1 and 2, the improved rail heat treating machine comprises a primary frame structure or carriage A and an operating

ed thereon. The main frame or carriage A is adapted to rest upon and be moved along rails R of a section of track, while the operating structure B carries a heating unit at each side thereof, a unit H_L being located over the left hand rail 5 of the track and a second unit H_R located over the right hand rail of the track. It will be noted that the operating structure B also carries gas controlling devices C substantially at the center thereof and located for ready access by the operator.

It is desired to have the entire apparatus of a light and portable, but nevertheless sturdy and rigid, construction. Thus, the carriage A may be composed of suitable light weight welded tubing formed into a box-like shape comprising upper and lower transverse horizontally disposed members or braces 10, connected by longitudinal horizontally disposed braces 11 and a plurality of vertically disposed braces 12. At each of the four corners of the carriage A shoes or rests 13 are secured by means of bolts 14 threadedly engaged in the ends of the transverse horizontally disposed braces 10. Said shoes have suitable heat and wear resistant soles or bearing plates 15 attached thereto with bolts 16 and completely insulated electrically therefrom so as to prevent any improper operation of the track signalling system. Flanges 15a may be provided on the bearing plate at one side of the machine at least 20 so as to aid in positioning the heating units H_L and H_R with respect to the rails being treated.

It will be observed that the shoes 13 are of a rigid angular construction and form an efficient stationary support for the entire machine when 25 performing a heat treating operation. However, in order to allow the machine to be moved from one rail joint to the next, the shoes 13, at the rear of the machine, may be provided with suitable extensions or brackets 17 rigidly supported by 30 braces 17a and having bearing portions 18 (Figs. 2 and 3) for receiving the axles of flanged wheels 19 on which the entire machine may be wheeled along the track. To facilitate in this 35 operation, angularly disposed handle bars 20 45 may be welded to the braces 11 of the carriage A and strengthened by vertical supports 21 (Fig. 4) and a horizontal brace 22. The flanged wheels 19 and their supporting brackets 17 are arranged so that when the machine is resting upon the 50 shoes 13, the wheels 19 will not contact the tread surfaces of the rail (see Fig. 3). By bearing down on the handle bars 20, however, the apparatus will be fulcrumed upon the rear shoes 13 and bring the wheels 19 into contact with the rail. 55

Further depression of the handle bars will cause the entire apparatus to be raised from the track and supported upon the wheels so that it may be moved to another position. Handles 23, supported by parallel spaced arms 24, which may be secured to the frame by means of the bolts 14 for the shoes 13, are provided at each side of the machine for lifting the entire apparatus from the track in order to carry it from one place to another.

Operating or secondary frame structure B, in a general sense, comprises three transverse tubular members or braces 25 which are positioned at the corners of a triangle and welded or otherwise fixedly secured at their opposite ends to end plates 26. By means of inwardly extending bosses or lugs 27 provided on the upper corners of the plates 26, the operating structure B is slidably mounted on two shafts 28, one of said shafts 20 being located at each side of the apparatus. The opposite ends of each of the shafts 28 are journaled in bearings 29 provided on the upper ends of four vertically disposed supporting arms 30. At its lower end, each of the arms 30 is pivotally attached by means of a pin or bolt 31 to a lug 32 provided on the inner lower corner of the adjacent shoe 13. From the foregoing it will be apparent that by means of the arms 30 the entire structure B is pivotally mounted for oscillatory or reciprocatory movement upon the primary supporting frame A. Such movement of the operating structure is desired for imparting a corresponding oscillatory movement to the heating units H_L and H_R which, as mentioned above and 35 will be described more particularly hereinafter, are carried on each side of the operating structure B.

In order to impart an oscillating or reciprocating movement to the operating structure B a lever 33 is pivoted upon a bracket 34 which is secured to one of the handle bars 20. The forward end of the lever 33 is pivotally connected to one end of a link 35, the other end of which is pivotally secured upon the rearward end of one of the shafts 28. Thus, by moving the lever 33 from side to side the operating structure may be oscillated. It is desirable to limit this movement, however, and for accomplishing this purpose a U-shaped yoke 36 is provided on or formed integrally with the upper end of one of the shoes 13, as best shown in Figs. 2 and 3. The arms of this yoke are positioned on either side of the adjacent supporting arm 30 so that as said arm 30 pivots about its associated pin 31 during the oscillating movement it will be limited in its movement by contact with the arms of the yoke. Adjustment of the oscillating movement may be effected by means of adjusting screws 37 provided in the arms of the yoke. By moving these screws inwardly or outwardly, the effective distance between the arms of the yoke may be varied, thereby varying the amplitude of the oscillatory movement of the frame B.

The heating units H_L and H_R may be of any suitable construction in which a source of high temperature heat, such as an oxy-fuel gas flame, an electric arc or the like, is utilized to heat the body of metal being treated. Those shown in the present instance are similar in general construction and operation to the heating unit disclosed in H. S. George application, Serial No. 25,567, filed June 8, 1935. Thus, as shown particularly in Figs. 3 and 5, each of the units H_L and H_R comprises two heating heads or manifolds 40 and 41 which are adapted to be connected to a con-

venient source of gaseous fuel by means of hollow tubular connections 42 and 43 respectively. Three nozzles or heating tips 44 are mounted in the underside of each of the manifolds 40 and 41 with two of each group of nozzles disposed adjacent and above the inside edges of the abutting rails R, and the remaining one disposed adjacent and above the outside edge, so that substantially triangular or trapezoidal shaped heat treated areas may be produced in the tread surfaces (see Fig. 6).

One of the heating heads is preferably adjustable longitudinally of the rails R with respect to the other, and both of said heads are vertically adjustable so as to vary or adjust the distance between the ends of the nozzles and the tread surfaces of the rails R. To this end the tubular connections 42 and 43 are clamped between the sections of split holding blocks 45 and 46 respectively, the sections of said blocks being held together by means of thumb screws 47 so as to maintain the heating heads in any adjusted vertical position. The block 45 is secured to the plate 26 by means of an angular bracket 48 bolted to said plate and welded to said block. However, the block 46 is slidably mounted on guide rods 50 fixed in the block 45, and is movable for adjustment on said rods by means of a positioning screw 51 which is threadedly engaged in the block 46 and journaled in a plate or bar 52 connecting the ends of the guide rods.

With the above described construction one of the heating heads may be adjusted longitudinally of the rail with respect to the other. However, rather than having to rely upon a positioning of the entire apparatus in order to locate the fixed heating heads properly with respect to the end of a rail joint, it is desirable to make some provision for moving the operating structure B longitudinally with respect to the rails. Accordingly, a shaft 54 having handles 55 at each end thereof is journaled in suitable bearings provided in each of the plates 26 and, as shown in Fig. 3, is located below the shafts 28. Pinions 56 are mounted on opposite ends of the shaft 54 for engagement with suitable rack teeth 57 provided on the lower side of each of the shafts 28. This construction is shown in Figs. 3 and 5, where it will be seen that by turning either of the handles 55 the operating structure B may be moved along the shafts 28 so that the fixed heating head 40 may be located in the desired position with respect to the end of a rail when starting a heat treating operation.

When the heating units are in operation, the flames issuing from the blowpipe nozzles 44 are reflected back from the tread surface of the rail and cause said nozzles to become overheated. To prevent any backfiring which may occur as a result of the preignition of the gases before issuing from the orifices of the nozzles 44, a suitable copper baffle plate 58 may be provided between the nozzles of each blowpipe and, as shown in Fig. 3, is adjustably and removably suspended from the guide rods 50 by means of supporting arms 59. This baffle is adapted to increase the circulation of air about the nozzles and remove heat from the region of said nozzles, it preferably being of the type disclosed in the application of H. S. George, filed December 24, 1936, Serial No. 117,506.

Gases may be supplied to the heating units from any suitable source. For example, oxygen and acetylene cylinders, together with suitable pressure regulators, may be carried on a push car

which is adapted to travel along the track as the heat treating operations progress. Flexible tubing in sufficient lengths is provided to connect such cylinders with the gas controlling devices C 5 on the apparatus, an acetylene tube 60 being connected to an acetylene inlet 61 and an oxygen tube 62 being connected to an oxygen inlet 63.

Separate gas controls are provided for each of the heating units H_L and H_R, although the gas 10 pressures are regulated at the supply cylinders. Accordingly, as shown in Figs. 1 and 2, the gases supplied to the heating unit H_R are controlled by an acetylene shut-off valve 64 and an oxygen shut-off valve 65, which are connected to their 15 respective acetylene and oxygen inlets 61 and 63. The two valves are interconnected for simultaneous actuation by means of a handle 66 and are mounted in a convenient location for ready access by the operator on the left hand portion of the 20 upper side of a rectangular sheet metal housing 67. This housing 67 is in turn secured to the upper braces 25 of the operating frame structure B by means of brackets 68. A suitable conduit 70 connects the acetylene shut-off valve 64 with the lower portion of a mixer 71 carried by a special 25 supporting bracket 72 which is secured to the braces 25 in any convenient manner. Acetylene passes through this lower portion of the mixer 71, without being mixed with any oxygen, into a 30 coil 73 comprising an elongated tubular conduit, the opposite end of which is connected to the central or mixing portion of the mixer 71. This coil 73 greatly improves the flashback resistance of the heating apparatus and is disposed inside of 35 the housing 67 in order that it may not become battered or broken during handling of the machine while in operation. Oxygen passes directly from the valve 65 to the mixer through a conduit 74 and is there properly mixed with the 40 acetylene so that a suitable combustible mixture may be led from the mixer 71 to the heating unit H_R. For this purpose, a conduit 75 connects the outlet side of the mixer with a Y-fitting or connection 76 from which branch conduits 77 and 78 lead the combustible mixture to the tubular connections 42 and 43 respectively of the heating unit H_R.

Similarly, the gases for the heating unit H_L are controlled by an acetylene shut-off valve 80 50 connected to the inlet 61 and a shut-off valve 81 connected to the inlet 63, which valves are simultaneously actuated by means of a handle 82. Acetylene passes from the valve 80 through a conduit 83 to the lower portion of a mixer 84 which is supported upon the frame B by a special bracket 84a (Fig. 4). From the mixer the acetylene passes through a coil or elongated conduit 85, similar to the coil 73, and then back to the mixer. The coil 85 is disposed in the housing 67 on the 55 side thereof adjacent to the handles 66 and 82 as shown in Fig. 4. Oxygen is led directly to the mixer 84 from the valve 81 by means of a conduit 86, and the combustible mixture passes from the outlet side of the mixer 84 through a conduit 87 to a Y-fitting or connection 88. Branch conduits 90 and 91 lead the combustible mixture from the outlet side of the fitting 88 to the tubular connections 42 and 43 respectively of the heating unit H_L.

From the foregoing it will be noted that the 70 handle 82, on the right hand side of the housing 67, controls the gas supply for the heating unit H_L; while the handle 66, on the left hand side of the housing 67, controls the gas supply for the heating unit H_R. Should it be desired to control

the gases for the heating units H_R and H_L from the right and left hand shut-off valves respectively, the conduits and mixers may be rearranged as shown diagrammatically in Fig. 9, wherein like reference characters indicate corresponding parts shown in Figs. 1, 2, and 4. It will be noted that the valves 80 and 81, mounted on the right hand side of the housing 67, lead the acetylene and oxygen to the mixer 84 from which the combustible mixture is led to the Y-fitting 88 which, in this 10 instance, is connected to the heating unit H_R; and the valves 64 and 65 control the flow of acetylene and oxygen directly to the mixer 71, from which the combustible mixture is led to the Y-connection 76 for the heating unit H_L. This arrangement of the gas controlling devices may be 15 considered preferable to that described above since it tends to avoid any confusion during the operation of the heat treating apparatus.

For igniting the combustible gas mixture at the 20 nozzles 44, a pilot burner P may be employed. As shown in Figs. 1, 2, and 5, such a burner may comprise the end of a metallic tubing 92 which is disposed adjacent the nozzles 44 and supported from the plate 26 by means of a bracket 93. The 25 tubing 92 extends upwardly and towards the center of the machine to a push button 94 which is part of a partially open valve connected to the acetylene inlet 61 by means of a conduit 95. Push button 94 is provided for opening the partially open valve further when it is desired to increase the size of the continuously burning pilot flame to ignite the gas at the nozzles 44.

The method of operating the above described 30 heat treating apparatus is substantially as follows: In heat treating tread surface areas at rail joints in a section of track, certain preliminary adjustments are made before heat treating the first rail joint. When the apparatus is placed upon a section of track, the joints of which are 35 to be heat treated, it is moved on the wheels 19 and brought to rest with one of the heating units positioned directly over the first rail joint to be treated. Assuming that the first joint to be treated is in the right hand rail R, the entire 40 apparatus is shifted by sliding on the shoes 13 until the flange 15a is in contact with the side of the rail. With the flange 15a in contact with the inner edge or side of the rail head, the nozzles 44 will be located at the desired position between 45 the inner and outer edges of the rail. In operating on rails of different sizes having wider or narrower rail heads, different bearing plates may be substituted for the plates 15 and having the flanges 15a thereof properly located so as to position the nozzles 44 accurately on such wider or 50 narrower rail heads. If desired, the shoes 13 could be provided with slots for receiving the bolts 16 and thereby allowing the bearing plates 15 to be adjusted laterally with respect to the rail head. The tips of the nozzles are then correctly 55 positioned for height above the tread surfaces of the rails by loosening the thumb screws 47 and raising or lowering the tubular connections 42 and 43. Next, the group of nozzles 44 connected to each of the manifolds 40 and 41 are properly 60 positioned lengthwise of the rail from the extreme end thereof. This may be accomplished by turning the handle 55, which moves the entire operating frame B, until the fixed manifold 40 is 65 located the desired distance from the end of the rail; and then the end of the positioning screw 51 may be turned, sliding the block 46 along the guide rods 50, to locate the manifold 41 a corresponding distance from the adjacent rail end. 70

In adjusting the elevation and position of the nozzles 44 a suitable gage may be employed, if desired.

With the nozzles properly positioned above the tread surfaces and from the extreme ends of the rails, the screws 37 in the arms of the yoke 36 are initially adjusted at the first rail joint to limit the oscillatory or reciprocatory movement that can be imparted to the nozzles by moving the lever 33. It will be understood that the position of the nozzles and the limit of their oscillatory movement are such that the gas flames are not directly applied to the inner and outer edges, nor to the extreme end edges of the rail tread surfaces. The conduction of heat to the extreme side edges and corners of the tread surfaces from the heated portions adjacent thereto is sufficient to heat such parts so that uniformity of temperature in the heat treated areas is attained. Similar adjustments are then made for the heating unit H_L on the opposite side of the machine, moving the machine to a rail joint in the left hand rail R, if necessary. The valves and pressure regulators for the acetylene and oxygen are then adjusted to deliver said gases at the proper pressures at the control valves 64, 65, 80, and 81, so as to produce flames having the proper rate of heat output and the proper or desired quality, such as neutral or a slight excess of acetylene. Such adjustments may be maintained substantially constant throughout the operation of the machine, unless both heating units H_R and H_L are to be operated simultaneously, when a readjustment would be required. It will be apparent that the adjustments of the gas supply at the supply cylinders will not be affected by operation of the control valves through the handles 66 or 82.

When the above described preliminary adjustments have been made, the pilot burners P are lighted and the apparatus is ready for heat treating the first rail joint on the right hand rail R. The push button 94 is operated to increase the size of the pilot flame and the handle or lever 66 for the valves 64 and 65 is moved to its open position to deliver oxygen and acetylene to the nozzles 44 in the heating unit H_R. Simultaneously with the lighting of the nozzles the operator oscillates said nozzles through a small arc by moving the lever 33 from side to side. By observing a timing device 96, conveniently located on the horizontal brace 22, the length of time the heat is applied to the tread surface areas can be accurately determined, and, at the end of a predetermined length of time, the handle 66 is moved to its closed position. The apparatus is then raised upon the wheels 19 and moved to the next rail joint in the section of track being treated. This joint will be located in the left hand rail R so that the heating unit H_L will be utilized for the next heat treating operation. However, since the preliminary adjustments have already been made, it is only necessary to position the nozzles from the extreme ends of the rails by manipulation of the handle 55 and positioning screw 51. When this has been accomplished the push button 94 for the heating unit H_L is depressed and the handle 82 moved to open position to light the nozzles in said unit. Oscillation or reciprocation of this heating unit H_L is effected by the same lever 33 and the entire heat treating operation is otherwise the same as that already described for the heating unit H_R.

In Figs. 7 and 8 there is shown a modified construction for the primary frame structure or

carriage A, which is particularly adapted for the continuous treatment of the entire rail tread surfaces in a section of track, although braking and/or locking devices are provided so that the apparatus may be used for treating the restricted tread surface portions adjacent a rail joint. Such a modified carriage A' is similar to the carriage A and is composed of suitable light weight welded tubing formed into a box-like shape comprising upper and lower transverse horizontally disposed members 110, connected by longitudinal horizontally disposed braces 111 and a plurality of vertically disposed braces 112. At each of the four corners of the carriage A' shoes 113 are secured by means of bolts 114 threadedly engaged in the ends of the transverse horizontally disposed members 110. It will be noted that the shoes 113, in the present instance, are not used to form a stationary support for the entire machine, but, on the contrary, are primarily provided for the purpose of supporting suitable extensions or brackets 117 at each corner of the machine. These brackets 117 are rigidly supported by means of braces 117a and are provided with bearing portions 118 for receiving the axles of flanged wheels 119 upon which the entire machine is supported and adapted to be wheeled along the track. The wheels 119 are preferably mounted in roller or ball bearings and, as shown in Fig. 7, are insulated electrically from the frame of the carriage by suitable insulation 118a provided about the axles in the bearing portions 118 so that any improper operation of the track signalling system will be prevented.

To facilitate the operation of moving the apparatus along the track upon the wheels 119, angularly disposed handle bars 120 may be welded to the braces 111 of the frame A' and strengthened by vertical supports 121 and a horizontal brace 122. Handles 123, supported by parallel spaced arms 124 which may be secured to the frame by means of the bolts 114, are provided at each side of the machine for lifting the entire apparatus from the track in order to carry it from one place to another.

In order to stop the apparatus in its movement, or lock it in any adjusted position upon a track, a special braking or locking device is provided on the forward end of the carriage A'. One satisfactory form of braking mechanism may comprise a brake lever 97 pivotally connected by means of a headed pivot pin 98 to each of the forward bearing members 118. These brakes are resiliently held in the position shown in Fig. 8 by recoiling springs 99 encircling the headed pivot pins 98, but are adapted to be turned about their pivots and into contact with the adjacent rail so as to stop or hold the apparatus in any adjusted position. Brake shoes 97a are provided on the contacting portions of each brake lever and insulated electrically therefrom in any suitable manner. An eccentric sprocket 100 is rigidly secured to each brake adjacent the pivot thereof and has an operating chain 101 engaging the sprocket teeth. One end of this chain is rigidly connected to the inside or lower edge of the eccentric sprocket 100 in such a manner that when the chain is pulled about the sprocket the brake will be turned about its pivot and into contact with the rail. Thus, the opposite end of each chain 101 is connected through a guide rod 102 and a spring 102a to a roller unit 103 which is adapted to slide along a tubular guide or cross arm 104 extending outwardly from either side of a vertically disposed supporting mem-

ber 105. Both the cross arm 104 and the vertically disposed supporting member 105 are centrally located at the front of the carriage A' and rigidly secured to the members 110 by means of a plurality of braces 106.

Each of the roller units forms part of a toggle brake actuating mechanism and is pivotally connected to one end of a hook-shaped link 107. The opposite hooked end of each link 107 is pivoted to one end of a double crank arm or toggle member 108 which is centrally pivoted to the upper end of the vertically disposed member 105. The crank arm 108 is adapted to be actuated by an elongated handle or lever 109 which is rigidly secured thereto by means of bolts 108a and spaced therefrom by spacing bushings 109a.

In Figs. 7 and 8 the braking mechanism is shown in inoperative position. It will be apparent, however, that when the handle or operating lever 109 is moved substantially 180° in a clockwise direction, the roller units 103 will be moved inwardly along the cross arm 104 so as to rotate the brake levers 97 about their pivots 88 and into firm and secure contact with the associated rails. It will be noted that when the crank arm 108 and links 107 are in their inoperative position, such parts are in a dead center position; and likewise when the handle 109 is rotated substantially 180°, the parts will again occupy a substantially dead center position so that the brakes 97 will remain in contact with the rails without any force being applied to the handle. When it is desired to release the brake, the handle 109 is raised and will spring back into its inoperative position.

Except for the fact that four wheels are provided so that the apparatus may be easily moved along a track, and a braking or locking mechanism is provided to hold the carriage in any adjusted position, the heat treating apparatus including the modified carriage A' is entirely similar to the first described apparatus comprising the primary frame or carriage A and the operating frame structure B. Thus, shafts 128 are provided at each side of the machine for slidably receiving an operating frame structure B, and said shafts 128 are pivotally supported on the upper ends of four vertically disposed supporting arms 130. Said arms 130 are pivotally mounted like the arms 38 so that the entire operating frame supported on the shafts 128 may be oscillated by means of a lever 133 and link 135.

If desired, a three-sided shield 149, composed of copper or other suitable material, may be secured to the shoes 113 at each side of the machine, as shown in dot and dash lines in Figs. 7 and 8. Such a shield will tend to prevent the flames from spreading and thereby protect the operator and parts of the apparatus from the intense heat produced in the two heating units.

It will be understood that if the apparatus is utilized to treat the tread surfaces of both rails simultaneously, then both heating units may be adjusted simultaneously along the shafts 128 and likewise may be oscillated or reciprocated over the rail tread surfaces simultaneously by actuation of the lever 133. During such operation the carriage A' may be moved at the desired and predetermined rate of speed by the operator. However, means may be provided for propelling the carriage along the track, if desired. For this purpose a motor properly geared to one of the wheels 119 would be suitable.

Various changes may be made in the construction and certain features thereof may be em-

ployed without others, without departing from the present invention or sacrificing any of its advantages.

What is claimed is:

1. Apparatus for heat treating tread surface areas of rails, comprising the combination of a carriage adapted to rest upon and be moved along a track; a supporting member pivotally mounted on said carriage; heating units carried by said supporting member, one unit being disposed over each rail of the track; and means for oscillating said pivotally mounted supporting member so that both of said heating units may be oscillated simultaneously over their respective rails. 10

2. Apparatus for heat treating tread surface areas of rails, comprising the combination of a carriage adapted to rest upon and be moved along a track; a supporting member pivotally mounted on said carriage; heating units carried by said supporting member, one unit being disposed over each rail of the track; and means for moving said supporting member longitudinally with respect to the rails so as to move both of said heating units simultaneously for adjustment. 15

3. Apparatus for heat treating tread surface areas of rails, comprising the combination of a carriage adapted to rest upon and be moved along a track; a supporting member pivotally mounted on said carriage; heating units carried by said supporting member, one unit being disposed over each rail of the track; means for moving said supporting member longitudinally with respect to the rails so as to move both of said heating units simultaneously for adjustment; and means for oscillating said pivotally mounted supporting member so that both of said heating units may be oscillated simultaneously over their respective rails. 25 30 35

4. Apparatus for heat treating tread surface areas of rails, comprising the combination of a carriage adapted to rest upon and be moved along a track; an arm pivotally connected to said carriage; a supporting member pivotally mounted on said arm; heating units carried by said supporting member with one unit disposed over each rail of the track; and means for oscillating said pivotally mounted supporting member so that said heating units may be reciprocated over the tread surfaces of the rails. 40 45

5. Apparatus for heat treating tread surface areas of rails, comprising the combination of a carriage adapted to rest upon and be moved along a track; an arm pivotally connected to said carriage; a supporting member pivotally mounted on said arm; heating units carried by said supporting member with one unit disposed over each rail of the track; means for moving said supporting member longitudinally with respect to the rail so as to locate said heating units properly for starting a heat treating operation; and means for reciprocating said pivotally mounted supporting member so that said heating units may be reciprocated over the tread surfaces of the rails. 50 55 60

6. Apparatus for heat treating tread surface areas of rails, comprising the combination of a carriage adapted to rest upon and be moved along a track; an arm pivotally connected to said carriage; a supporting member pivotally mounted on said arm; heating units carried by said supporting member with one unit disposed over each rail of the track; means for reciprocating said pivotally mounted supporting member so that said heating units may be reciprocated over the tread surfaces of the rails; and means cooperat- 65 70 75

ing with said arm for limiting the reciprocatory means for oscillating said operating frame so as to effect a corresponding movement in the source of high temperature heat, said oscillating means comprising a lever fulcrumed on the carriage and a link pivotally connected at one end to said lever and at its other end to one of the vertically disposed arms. 5

7. Apparatus for heat treating tread surface areas of rails, comprising the combination of a carriage adapted to rest upon and be moved along a track; a plurality of arms pivotally connected to said carriage; a supporting frame pivotally mounted on said arms; heating units carried by said supporting frame, one unit being disposed over each rail of the track; and means for oscillating said pivotally mounted supporting frame so that both of said heating units may be oscillated simultaneously over their respective rails. 10

8. Apparatus for heat treating tread surface areas of rails, comprising the combination of a carriage adapted to rest upon and be moved along a track, said carriage being substantially rectangular in shape; a vertically disposed supporting arm pivotally connected to each of the four corners of said rectangular carriage; an operating frame pivotally connected to said arms; a source of high temperature heat mounted on said operating frame; and means for oscillating said operating frame so as to effect a corresponding movement in the source of heat carried thereby. 15

9. Apparatus for heat treating tread surface areas of rails, comprising the combination of a carriage adapted to rest upon and be moved along a track, said carriage being substantially rectangular in shape; a vertically disposed supporting arm pivotally connected to each of the four corners of said rectangular carriage; a shaft at each side of said carriage and journalled at its ends in the adjacent supporting arms; an operating frame slidably mounted on said shafts; a source of high temperature heat carried by said operating frame and disposed above the tread surface of one of the rails of the track; and means for oscillating said operating frame so as to effect a corresponding movement in the source of high temperature heat. 20

10. Apparatus for heat treating tread surface areas of rails, comprising the combination of a carriage adapted to rest upon and be moved along a track, said carriage being substantially rectangular in shape; a vertically disposed supporting arm pivotally connected to each of the four corners of said rectangular carriage; a shaft at each side of said carriage and journalled at its ends in the adjacent supporting arms; an operating frame slidably mounted on said shafts; a source of high temperature heat carried by said operating frame and disposed above the tread surface of one of the rails of the track; means for oscillating said operating frame so as to effect a corresponding movement in the source of high temperature heat; and means for moving said operating frame along said shafts so as to position said source of heat properly for starting a heat treating operation. 25

11. Apparatus for heat treating tread surface areas of rails, comprising the combination of a carriage adapted to rest upon and be moved along a track, said carriage being substantially rectangular in shape; a vertically disposed supporting arm pivotally connected to each of the four corners of said rectangular carriage; a shaft at each side of said carriage and journalled at its ends in the adjacent supporting arms; an operating frame slidably mounted on said shafts; a source of high temperature heat carried by said operating frame and disposed above the tread surface of one of the rails of the track; and

means for oscillating said operating frame so as to effect a corresponding movement in the source of high temperature heat, said oscillating means comprising a lever fulcrumed on the carriage and a link pivotally connected at one end to said lever and at its other end to one of the vertically disposed arms. 5

12. Apparatus for heat treating tread surface areas of rails, comprising the combination of a carriage adapted to rest upon and be moved along a track, said carriage being substantially rectangular in shape; a vertically disposed supporting arm pivotally connected to each of the four corners of said rectangular carriage; a shaft at each side of said carriage and journalled at its ends in the adjacent supporting arms; an operating frame slidably mounted on said shafts; a source of high temperature heat carried by said operating frame and disposed above the tread surface of one of the rails of the track; means for oscillating said operating frame so as to effect a corresponding movement in the source of high temperature heat, said oscillating means comprising a lever fulcrumed on the carriage and a link pivotally connected at one end to said lever and at its other end to one of the vertically disposed arms; and a yoke mounted on the carriage and having arms disposed on either side of one of said supporting arms for limiting the oscillatory movement of the operating frame. 10 15 20 25 30

13. Apparatus for heat treating tread surface areas adjacent the ends of rails at a rail joint, comprising the combination of a carriage adapted to rest upon and be moved along a track; a supporting member mounted on said carriage; a heating unit carried by said supporting member and including two sources of high temperature heat, one of said sources being fixed with respect to said supporting member and the other of said sources being movable longitudinally of the rail; means for moving said supporting member longitudinally of the rail so as to position said fixed source of heat properly with respect to the end of a rail; and means for moving said other source of heat longitudinally of the rail while the supporting member and said first mentioned source of heat remain stationary. 35 40 45

14. Apparatus for heat treating tread surface areas of rails, comprising the combination of a carriage adapted to rest upon and be moved along a track; wheels mounted on said carriage and normally out of contact with the rails when the carriage is at rest on the track; a supporting member pivotally mounted on said carriage; a source of high temperature heat carried by said supporting member and adapted to be disposed above the tread surface of a rail; and means for oscillating said pivotally mounted supporting member so as to effect a corresponding movement in the source of high temperature heat. 50 55 60

15. Apparatus for heat treating tread surface areas of rails, comprising the combination of a carriage adapted to rest upon and be moved along a track; an operating frame pivotally mounted on said carriage and adapted to be moved longitudinally of the rails with respect to said carriage; heating means mounted on said operating frame and including an oxy-fuel gas blowpipe disposed over each rail of the track; and gas controlling means centrally mounted on said operating frame for ready access by the operator. 65 70
